UNITED STATES PATENT OFFICE.

HIO P. EILERS, OF CLEVELAND, OHIO.

BOLT-THREADING MACHINE.

SPECIFICATION forming part of Letters Patent No. 637,772, dated November 28, 1899.

Application filed February 26, 1898. Serial No. 671,806. (No model.)

To all whom it may concern:

Be it known that I, HIO P. EILERS, a citizen of the United States, and a resident of Cleveland, county of Cuyahoga, and State of Ohio, have invented a new and useful Improvement in Bolt-Threading Machines, of which the following is a specification, the principle of the invention being herein explained and the best mode in which I have contemplated applying that principle, so as to distinguish it from other inventions.

My invention has for its object the improvement of threading-heads of bolt-threading machines; and it consists of means hereinafter fully described.

The annexed drawings and the following description set forth in detail certain mechanism embodying the invention, such disclosed means constituting but one of various mechanical forms in which the principle of the invention may be used.

In said annexed drawings, Figure I represents a perspective view of my improved threading-head. Fig. II represents a cross-section taken upon the axial plane indicated by line 2 2 in Fig. I. Fig. III represents a cross-section taken upon the axial plane indicated by the said line 2 2, illustrating the relative position of the parts when the head is open. Fig. IV represents a cross-section taken upon the axial plane indicated by line 4 4 in Fig. I, showing portions of the mechanism in elevation. Fig. V represents a sectional view taken upon the axial plane indicated by said line 4 4, showing the relation of the parts when said parts are in the position shown in Fig. III. Figs. VI, VII, VIII, IX, and X are detail views.

The barrel A is formed with a longitudinal bore α and an end flange α' , by means of which it may be secured to the rotating spindle of the threading-machine. Four radial slots α^2 are cut in the end of said barrel, Fig. X, the distance from each other of whose centers is ninety degrees. In each lateral face of each slot are cut two tongues α^3 , Figs. II, III, and X.

Four slides or die-holders B, Figs. VI and IX, are each of a thickness such as to cause them to snugly slide into the slots α^2 and are formed on each lateral face with two grooves b , adapted to receive the tongues α^3 . The

grooves are both formed nearer one end of the slide than the other, whereby the latter when in position in the slots are caused to project beyond the end of the barrel. The slides are thus held rigidly against displacement in either direction of the barrel-axis and are capable of radial retraction only. The outer end face b' of each slide is inclined with reference to the face opposite, such inclination being toward the inner end of each slide. An undercut or inverted T-groove b^2 is formed in each slide parallel with and cut from the middle of the inclined face thereof.

In the outer lateral end b^3 of each slide is cut a groove b^4 , into each of which fits a cutter or die C, which is removably secured by means of a set-screw B', threaded in a bushing b^5 , suitably secured in the slide.

Bearing upon and projecting beyond the end of the barrel is a die-ring D, upon whose inner surface are secured four tongues D' of T cross-section and distant from each other ninety degrees. Said tongues are given an inclination equal to that of the T-grooves in the slide and made to fit and slide in said grooves. The ring may hence be slipped upon the barrel and the tongues caused to engage the grooves, whereby the retraction of the ring will cause the said slides to radially retract toward and from the barrel-axis. The inner projecting surface is of beveled or inclined formation, as shown in Fig. IV. Diametrically opposite each other, nearer the opposite end of the barrel, are formed or secured two racks E. A retractable sleeve F has sliding bearing upon said barrel and is formed with grooves f, whereby it may pass said racks. Said sleeve has formed upon it two pairs of lugs f', in each pair of which is secured a pin journaling one arm g of a toggle G. Said toggle-arm has formed upon it concentric with its bearing a set of gear-teeth forming a segment g', meshing with the rack E. The opposite end of the toggle is journaled upon a screw-bolt H, which is screwed into an elongated nut J, having an outer thread whose trend is in a direction opposite that of the inner thread. Said nuts are screwed into threaded bores diametrically opposite each other in the die-ring. When the sleeve F, and hence the toggle-arm bearing, is retracted to the right from the position shown in Fig.

IV, the toothed toggle-arm will be engaged by the rack, whereby the toggle will be actuated to roll, causing it to rotate on its bearing and to move in a cycloidal path. Such movement of the toggle operates the die-ring, causing it also to retract to the right, and hence radially retract and open the dies themselves, such operation taking place when it is desired to release a bolt upon which a thread has been cut. The relation of the parts when the dies are open is illustrated in Figs. III and V, and it will be seen that a given linear movement on the part of the sleeve produces more than twice the same amount of movement in the die-ring by virtue of the cycloidal movement imparted to the toggle. This feature permits the use of a degree of inclination in the grooves b^2 of the slides less than that which would otherwise be required to cause a given amount of opening movement on the part of the dies for a given amount of movement on the part of the sleeve. The inclination being thus less, it is obvious that a nicer adjustment of the dies may be obtained.

25 The adjustment of the dies is brought about by turning the nut J, which is provided in its end with a slot for the insertion of a screw-driver for that purpose. When the sleeve is in its extreme position to the left, as shown in Fig. IV, the middle of the toggle rests upon the barrel, as shown, and a line $x\text{--}x$, drawn through the center of the left-hand pin through the center of the middle pin, will intersect the pitch-line of the teeth of the gear and rack perpendicularly below the center of said gear. The toggle when in this position is effectually locked, and the trend of the threads on the inside and outside of the adjusting-nut being in opposite directions it is seen that it is impossible for the nut to turn itself through the pressure of the work or jar of the machine, and hence change the position of the dies, so that while the thread is being cut the dies are absolutely rigid and independent of any jars which would tend to alter the relation of the parts; but when the thread is not being cut it is possible to adjust the nut at any time, and the turning of the nut will produce a corresponding movement 40 of the die-ring, which hence alters the relation between the said sleeve and the die-ring and the dies held therein.

50 The slides projecting beyond the end of the barrel makes it possible to permit the dies to be located beyond the said end and, further, permits the sides of that part of the slides which directly supports the dies to be free. The slides always bear against the die-ring, and hence a plane perpendicular to the barrel-axis and passing through the end portion of a die will intersect the outer bearing-surface of the slide holding such die when in the position shown in Fig. I, said ring thereby forming a support or backing to receive radial outward thrusts exerted upon the dies during the cutting operation. This construction prevents the slide from binding in the

grooves in the barrel end, so that on the completion of the cutting operation the dies may be easily withdrawn from the threads. The outer lateral face of each slide is free, and hence the outer lateral face of each die may be free. The sides of the slides being free, as described, the chips formed during the cutting operation find a free exit between the slides, and hence the possibility of clogging up the inside of the head is avoided. The inner surface of the die-ring being beveled, as described and shown, the chips are not permitted to remain in the die-throat, but are discharged from the ring as soon as they drop upon it, thus still further contributing to the freedom from damage by the clogging or interference of the chips. The outer lateral face of the die being free, it is seen that it is possible to bring the said dies completely up under the head of the bolt upon which a thread is being cut.

It is very essential that the groove b^2 be formed and the tongue D' be secured to the parts as shown, inasmuch as a reversal of the arrangement—that is, securing the tongue to the slide and forming the groove in said ring—would necessitate a crossing of grooves in the slides, resulting in a disastrous destructive action on the part of the sharp corners so formed. My improvement hence combines the advantages of nicety of adjustment, absolute rigidity of parts during the cutting operation, freeness from clogging, ability to cut a thread throughout the entire length of a bolt, and simplicity of construction without unduly increasing its size.

Inasmuch as the dies themselves are independent of and removable from the slides, the black stock may be used, thus eliminating expense occasioned by dressing and finishing the hard die-steel, an item of considerable economical importance in the construction of bolt-threading machinery.

Other modes of applying the principle of my invention may be employed instead of the one explained, change being made as regards the mechanism herein disclosed, provided the means covered by any one of the following claims be employed.

I therefore particularly point out and distinctly claim as my invention—

1. In a bolt-threading machine, the combination of a barrel, slides fitted in and projecting from the end of said barrel and provided with dies in said projecting portion, and supporting means, said slides having a bearing-surface for engaging said supporting means, said surface intersecting a plane perpendicular to the barrel-axis and passing through the outer end portion of such die, substantially as set forth.

2. In a bolt-threading machine, the combination of a barrel, die-holding slides fitting in the end of said barrel and engaging said barrel in tongue-and-grooved formation, supporting means, said slides provided with an undercut groove for engaging a tongue having

a cross-section similar to the groove cross-section and secured to said supporting means, substantially as set forth.

3. In a bolt-threading machine, the combination of a barrel, slides fitting in and radially retractable in said barrel, and a supporting - ring projecting beyond the barrel end, the inner projecting surface of said ring having a beveled or inclined formation intermediate of said slides, substantially as set forth.

4. In a bolt-threading machine, the combination of means for retracting the dies, means for operating said retracting means, said operating means having a cycloidal movement, and means for actuating said operating means, substantially as set forth.

5. In a bolt-threading machine, the combination of means for retracting the dies, a toggle for operating said retracting means, said toggle having a cycloidal movement, and means for actuating said toggle, substantially as set forth.

6. In a bolt-threading machine, the combination of means for retracting the dies, means for operating said retracting means, means for actuating said operating means and means for imparting to said operating means a cycloidal movement, substantially as set forth.

30 7. In a bolt-threading machine, the combination of means for retracting the dies, a toggle for operating said retracting means, means for actuating said toggle and means for imparting to said toggle a cycloidal movement, substantially as set forth.

35 8. In a bolt-threading machine, the combination of means for retracting the dies, a

toggle for operating said retracting means, said toggle journaled solely on said retracting means and on a retractable bearing, and means 40 for imparting a rotary movement to one of said toggle-arms whereby the toggle has imparted to it a cycloidal movement, substantially as set forth.

9. In a bolt-threading machine, the combination of means for retracting the dies, a toggle for operating said retracting means, one end of said toggle secured to said retracting means and the other journaled on a retractable bearing said journaled end formed 50 with gear-teeth, and a rack engaging said gear-teeth, whereby said journaled arm is given a rotary movement when said bearing is retracted thereby imparting a cycloidal movement to said toggle, substantially as set 55 forth.

10. In a bolt-threading machine, the combination of means for retracting the dies, means for operating said retracting means, and means for adjusting the relation of said retracting and operating means, such adjusting means consisting of a nut adapted to be screwed into the retracting means and provided with a threaded bore adapted to receive the connecting portion of said operating means, the trend of the inner and outer threads being in opposite directions, substantially as set forth.

Signed by me this 24th day of February, 1898.

H. P. EILERS.
